MONOCHROMATOR

Dietmar M. Schoeffel, 355 Hillsdale Ave., Hillsdale, N.J.

Filed Apr. 18, 1961, Ser. No. 64,840

Term of patent 14 years

(Cl. D57—1)

The side not shown is substantially plain.

I claim:

The ornamental design for a monochromator, substantially as shown and described.
